US0D1091482S

(12) **United States Design Patent** (10) Patent No.: **US D1,091,482 S**
(45) Date of Patent: ** Sep. 2, 2025

(54) **OPTICAL CONNECTOR FERRULE**

(71) Applicant: **KYOCERA CORPORATION**, Kyoto (JP)

(72) Inventors: **Keita Suzuki**, Yokohama (JP); **Tetsuya Hata**, Yokohama (JP)

(73) Assignee: **KYOCERA CORPORATION**, Kyoto (JP)

(**) Term: **15 Years**

(21) Appl. No.: **29/926,150**

(22) Filed: **Jan. 29, 2024**

(30) **Foreign Application Priority Data**

Dec. 25, 2023 (JP) ..... 2023-026858 D

(51) **LOC (15) Cl.** **13-03**

(57) **CLAIM**

The ornamental design for an optical connector ferrule as shown and described.

DESCRIPTION

FIG. 1 is a front, top and right-side perspective view of an optical connector ferrule showing our new design;

FIG. 2 is a rear, bottom and left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

1 Claim, 5 Drawing Sheets
